UNITED STATES PATENT OFFICE.

JACOB L. SCHUREMAN, OF CHICAGO, ILLINOIS, ASSIGNOR, BY MESNE ASSIGNMENTS, TO THE CUTLER-HAMMER MFG. CO., OF MILWAUKEE, WISCONSIN, A CORPORATION OF WISCONSIN.

ELECTRICAL INTERLOCKING MECHANISM.

1,071,807.

Specification of Letters Patent.

Patented Sept. 2, 1913.

Application filed August 21, 1908. Serial No. 449,581.

To all whom it may concern:

Be it known that I, JACOB L. SCHUREMAN, a citizen of the United States, residing at Chicago, in the county of Cook and State of Illinois, have invented a new and useful Improvement in Electrical Interlocking Mechanism, of which the following is a specification.

My invention relates to automatically operated means for preventing the closing of a switch controlling the opening and closing of a circuit containing a switch-controlled resistance, or a series thereof, until the resistance, when but one is used, or all 15 or a part of the said resistances, when more than one is used, have been cut into the circuit, thereby to prevent overload upon the electrical apparatus in circuit with the resistance or resistances.

20 My object is to provide a novel and simple form of interlock for the above stated purpose of the mechanically operated type, to the end of rendering positive the interlocking of the circuit-closing switch.

25 Referring to the accompanying drawings, Figure 1 is a face view of an electrical starting apparatus illustrating my invention in connection therewith, the form of apparatus shown being of a well-known type 30 comprising a main line switch, and accelerated switches for controlling the series of resistance groups; Fig. 2 is an enlarged section taken at line 2 on Fig. 1 and viewed in the direction of the arrow, illustrating 35 the normal position of the accelerating switch adapted to be first operated for cutting out the resistances; Fig. 3 is an enlarged section taken at the line 3 on Fig. 1 and viewed in the direction of the arrow, and 40 Fig. 4 is a section taken at the line 4 on Fig. 1 and viewed in the direction of the arrow.

In the particular apparatus for controlling gradual cutting out of resistances in a 45 circuit to be supplied including a motor or other electrical device, in connection with which apparatus I have chosen to illustrate my invention, the supporting part, or plate, is indicated at 5, and as is usual in constructions of this kind, is intended to be secured on a support to extend in upright 50 position. Mounted on the face of this plate is a series of subsidiary switches 6, 7 and 8, which may be of any suitable construction, 55 those illustrated each comprising a bracket

9 secured to the plate 5 as by bolts 10 and provided with spaced arms 11; an arm 12 in the nature of a bell-crank lever fulcrumed near its angle as indicated at 13, to the arms 11 of the bracket 9; a pair of carbon 60 electrodes 14 slidably confined in the slotted upper end-portion of the arm 12 and each yieldingly pressed in a rearward direction by a spring 15; a link section 16 pivoted near its upper end as indicated at 17, to the 65 short arm 18 of the bell crank 12 and having its lower end expanded and recessed as illustrated to provide a shoulder 19 and clearances for a shaft hereinafter described; and a block 20 secured to the plate 5, as by 70 bolts 21, immediately below the switch in a position adapting it to be engaged by a finger 22 carried by the link 16 at its lower end.

Secured to the front of the plate 5 are 75 contacts 23 to 28 inclusive, which are arranged in two horizontal series, as represented, to be engaged by the respective pairs of electrodes carried by the switches 6, 7 and 8, these contacts having plates 29 to 34 80 inclusive, respectively, to which binding-posts (not shown) may be connected.

The means illustrated in the apparatus shown for producing operation of the switches 6, 7 and 8 in succession, comprises 85 a shaft 35 journaled in bearings 36, 36 to extend through the recesses in the lower expanded portions of the link sections 16, this shaft carrying a series of crank-pins 37, 38 and 39 spaced apart and each occupying a 90 different position about the circumference of the shaft, as represented in Fig. 1. These crank-pins are so arranged on the shaft 35 as to cause the pin 37 to rest normally against the shoulder 19 carried by the link 95 section 16 of the switch 6; the pin 38 to be spaced a slight distance away from the shoulder 19 of the switch 7; and the pin 39 to extend still farther away from the shoulder 19 of the switch 8, so that when the 100 shaft 35 is turned, as hereinafter described, it will cause the switches 6, 7 and 8 to be successively operated to closed position and thereby successively cut out portions of the resistances controlled thereby, as is well 105 understood in the art.

The means for rotating the shaft 35 are of the electrically-controlled solenoid type comprising a coil 40 adapted to be energized 110 in any suitable manner, and a core 41 op-

erating in the coil 40 and in a dash-pot 42. The core may operatively engage the shaft 35, to rotate it, in any suitable manner, as for instance by rack-and-pinion connection, 5 as is well known in the art, whereby when the core is drawn up into the coil, when the latter is energized, the shaft 35 will be turned in its journals 36.

Secured to the front side of the plate 5 10 is a main line switch 43 comprising two spaced arms 44, 44 of general bell crank shape fulcrumed on brackets 45 carried by the plate 5; an electrode 46 slidably mounted in the upper free end of each arm 44 and 15 yieldingly pressed rearwardly by a spring 47; a yoke-shaped frame member 48 journaled on a shaft 49 secured to the plate 5 as represented at 50; links 51 pivoted at their upper ends as indicated at 52 to the 20 short arms 53 of the bell cranks 44 and at their lower ends as indicated at 54 to the yoke 48 a slight distance to one side of the points at which the latter is journaled on the shaft 49; an arm 55 extending centrally 25 from the yoke 48; and an arm 56 pivotally connected with the outer end of the arm 55 as indicated at 57, and connected at its upper end with the core 58 of the solenoid 59. The electrodes 46 are designed to be moved 30 into and out of engagement with contacts 60 (one only of which is shown), secured on the front side of the board 5.

In the operation of the apparatus described, assuming the parts to be in the 35 normal position as illustrated in the drawings, a current caused to pass through the coil of the solenoid 59 energizes it, thereby drawing up the core 58 and arm 56, with the result of moving the electrodes 46 into 40 engagement with the opposed contacts 60 and closing the circuit through the coil 40 and the resistance groups (not shown) controlled by the switches 6, 7 and 8. The effect of thus causing current to pass through the 45 coils 40 energizes it thereby drawing up the core 41 with the result of rotating the shaft 35 and successively throwing in the switches 6, 7 and 8 by reason of the engagement of the crank-pins 37, 38 and 39 with the shoulders 19 on the respective switches, and successively cutting out the resistances controlled thereby, thus producing acceleration of the electric-motor or other device in the circuit with the resistances. In the normal 50 open condition of the switches 6, 7 and 8, the respective fingers 22 carried thereby are caused to bear against surfaces 61 on the blocks 20, as illustrated in Fig. 2. The engagement of the crank-pins with the shoulders 19 of the respective switches causes the latter to be closed with the result of carrying the arm 16 of each switch 6, 7 and 8 to a position in which its finger 22 engages 55 with a surface 62 on the block, and thus after the crank-pins have left the shoulders

with which they engage, the switch is prevented from dropping open. As means for preventing the accidental dropping out of the switches or manual opening thereof, I provide interlocking fingers 63 on the shaft 35, one of each of these fingers being disposed at a point diametrically opposite to each crank-pin 37, 38 and 39. Thus by the time each crank-pin has left its respective shoulder 19, the respective finger 63 has moved into a position in which it extends over the rounded surface 64 provided on the lower ends of the links 16.

When the main line switch 43 is opened it breaks the circuit through the switches 6, 7 and 8 and the solenoid-coil 40, and the shaft 35, under the weight of the core 41, turns in the opposite direction, thereby causing the cranks 37, 38 and 39 to successively throw the last referred to switches to open position and successively cut into circuit the various resistance-groups controlled thereby. It is manifest that this operation of returning the switches to normal condition in which all of the resistances controlled thereby are cut into circuit, is relatively slow, and thus if the main line switch after being opened is again closed before all of the switches 6, 7 and 8 have been returned to normal position, it will cause a rush of current through the motor or other device in the circuit and thus overload, with the well known disastrous results. To prevent the occurrence of overloading as described, I provide an interlocking device adapted to be controlled by the operation of the shaft for preventing the main line switch from being operated to close it when any of the switches 6, 7 and 8 are closed, the construction of which is as follows:

Journaled in rearwardly extending bearings 65, 65 on the rear side of the plate 5 is a yoke-shaped rocking member 66, the free outer rod-ends 67 and 68 of which extend through elongated relatively large openings 69 in the plate 5. The member 66 is so positioned as to cause the extreme outer end-portion of the rod 67 to normally bear, under the influence of a spring 70, against the face of a cam 71 carried on a disk 72 on the shaft 35. The rod-end 68 has a sleeve 73 of insulating material secured to it in the outer end-portion of which a rod 74 is secured, this rod 74, when the member 66 is in normal position as described, extending to one side of the adjacent switch arm 44 and thus out of its path of movement. Thus the normal position of the member 66 is that in which its end-portion 67 rests against the cam 71 and the rod 74 is out of the path of movement of the adjacent switch arm 44.

When the main line switch 43 is closed as described, the shaft 35 immediately com-

mences to turn to the left in Fig. 2, thereby successively closing the switches 6, 7 and 8 in the manner described. By the time the shaft 35 has turned sufficiently far to close the switch 6, the cam has been turned out of engagement with the rod-end 67 of the member 66 and the latter, under the influence of the spring 70, thereby turns in its bearing 65 to a position in which its rod 74 yieldingly bears against the side of the adjacent switch arm 44, the member 66 remaining thus spring-pressed so long as the cam 71 is out of engagement with the rod-end 67. Thus when the main line switch 43 is opened to break the circuit through the switches 6, 7 and 8 and the solenoid-coil 40, the arms 44 of the main line switch swing out sufficiently far to permit the rod 74 to swing to a position immediately under it, under the influence of the spring 70. The effect of this operation is to prevent the switch 43 from again being closed until the shaft 35 has turned to the right in Fig. 2 to a position in which the cam 71 again engages with the end 67 of the member 66 for moving the latter against the tension of its spring 70 and swinging the rod 74 out of the path of movement of the adjacent switch arm 44, this last referred to operation not taking place until all the switches 6, 7 and 8 have been opened.

It will thus be readily apparent that by so constructing the interlocking device its operation is rendered positive and reliable in preventing the closing of the circuit through the motor or other electrical device interposed in the circuit controlled by the switches 6, 7 and 8, until all of the resistances are interposed in the circuit.

While I have illustrated and described my invention as embodied in a starting device, the resistance-controlling switches of which are operated through the medium of a rotary shaft carrying cranks, I do not wish to be understood as limiting my invention to its use in connection with an apparatus in which said switches are operated in this manner, as any other suitable means may be employed for effecting the operation of the resistance-controlling switches. It is also to be understood that my invention is applicable to an apparatus in which but one switch controlling a resistance is employed or in which any other suitable number than that illustrated and described can be used, depending on the number of resistances to be controlled.

What I claim as new, and desire to secure by Letters Patent, is—

1. In combination with an electrically-operated main-line switch, a series of subsidiary switches, and electrical means for operating the subsidiary switches in succession, of a mechanical interlocking device constructed and arranged to prevent the

operation of said main line switch to close it while a predetermined number of said subsidiary switches are closed.

2. In combination with a main-line switch, a subsidiary switch, a rotary shaft, means on said shaft for operating said subsidiary switch, and means for rotating said shaft, of an interlocking device operated through the medium of said shaft and constructed and arranged to prevent the operation of said main line switch to close it while said subsidiary switch is closed. 70

3. In combination with a main-line switch, a subsidiary switch, and a movable member carrying means for engaging the subsidiary switch, when the member is moved, for closing said subsidiary switch, of an interlocking device constructed and arranged when actuated to prevent the operation of said main line switch to close it while said subsidiary switch is closed, and cam mechanism carried by said movable member and engaging with said interlocking device, for the purpose set forth. 80

4. In combination with a main-line switch, a subsidiary switch, and a movable member carrying means for engaging with the subsidiary switch, when said member is operated, of an interlocking device normally extending out of the path of said main-line switch and constructed and arranged to be moved into interlocking position through the medium of said movable member when said subsidiary switch is closed. 90

5. In combination with a main-line switch, a subsidiary switch, and a movable member carrying means for engaging the subsidiary switch to operate it when said member is moved, of an interlocking device mounted in a manner permitting it to be rocked and constructed and arranged to be operated through the medium of said movable member to prevent the operation of said main-line switch to close it when said subsidiary switch is closed. 105

6. In combination with a main-line switch, a subsidiary switch, and a movable member carrying means for operatively engaging said subsidiary switch to close it 115 when said member is moved, of an interlocking device for the main-line switch constructed and arranged to be held out of interlocking engagement with said main-line switch when said movable member occupies a position in which said subsidiary switch is open and to be moved into interlocking position when said movable member is moved to close said subsidiary switch. 120

7. The combination of a main-line switch, 125 a subsidiary switch, a rotary shaft, means on said shaft for operating said subsidiary switch, means for rotating said shaft, a main-line switch interlocking device constructed and arranged to be moved into and 130

- out of switch-interlocking position, and means on said shaft constructed and arranged to cause said interlocking device to be out of interlocking engagement when said shaft is in a position in which said subsidiary switch is open, and to move said interlocking device into interlocking position when the shaft is operated to close said last referred to switch.
8. The combination of a main-line switch, a subsidiary switch, a rotary shaft, means on said shaft for operating said subsidiary switch, means for rotating the shaft, a cam on said shaft, and an interlocking device for said main-line switch constructed and arranged to be engaged by said cam for holding it out of locking position when said subsidiary switch is open, and to be moved to locking position when said last referred to switch is closed.
9. The combination of a main-line switch, a subsidiary switch, a rotary shaft, means on said shaft for operating said subsidiary switch, an interlocking device comprising a rocking member adapted to be engaged at one end for moving its other end into and out of interlocking position, and means operated by said shaft for controlling the operation of said interlocking device, for the purpose set forth.
10. The combination of a main-line switch, a subsidiary switch, a rotary shaft, means on said shaft for operating said subsidiary switch, means for rotating said shaft, an interlocking member constructed and arranged to be moved into and out of position for locking said main-line switch to prevent closure thereof, means tending to move said interlocking device into a position in which it engages with said main-line switch for holding it open, and means carried by said shaft constructed and arranged to hold said interlocking device out of locking engagement with said main-line switch when said shaft is in a position in which said subsidiary switch is open and permit said interlocking device to be moved to locking position when the shaft is in a position in which the said subsidiary switch is closed.
11. The combination of a main-line switch, a subsidiary switch, a rotary shaft, means on said shaft for operating said subsidiary switch, means for rotating said shaft, an interlocking device comprising a two-armed member, one of which arms extends adjacent to said shaft and the other adjacent to said main-line switch, means tending to move said interlocking device into a position in which one of its arms interlocks with said main-line switch, and a shoulder on said shaft constructed and arranged to hold said main-line-switch-engaging arm out of interlocking position when the shaft is in a position in which said subsidiary switch is open, and to permit said last referred to arm to be moved into interlocking position when said subsidiary switch is closed.
12. The combination of a main-line switch, a subsidiary switch, a rotary shaft, means on said shaft for operating said subsidiary switch, means for rotating said shaft, a yoke-shaped member constructed and arranged to be rocked, to move into and out of locking engagement with said main-line switch, means tending normally to move said interlocking device into locking position with said main-line switch, and means on said shaft constructed and arranged to cause said interlocking device to be out of engagement with said main-line switch when the shaft is in a position in which said subsidiary switch is open, and to permit said interlocking device to be moved into interlocking position when said last referred to switch is closed.
13. In combination, an electro-responsive main switch, an electro-responsive subsidiary switch arranged substantially parallel thereto, and a mechanical interlock between said switches necessitating opening of said subsidiary switch prior to closure of said main switch but permitting said main switch to open regardless of the position of said subsidiary switch.
14. In combination, a supporting panel, a main switch, and a subsidiary switch mounted upon said panel and movable in substantially parallel planes, and an interlocking device mounted on the rear of said panel and having portions projecting therethrough, said interlocking device being controlled by said subsidiary switch to necessitate opening of the same prior to closure of said main switch.
15. In combination, a main switch, a rheostat-operating member, an interlocking device normally biased to a position to prevent closure of said main switch, and a revolute cam movable with said rheostat-operating member for operating said interlocking device to permit closure of said main switch, but necessitating the return of said operating member to full off position prior thereto.
16. In combination, a main line switch, a subsidiary switch, an interlocking device biased to a position in the path of said main switch to prevent closure thereof, and a revolute cam movable with said subsidiary switch for moving said device out of the path of said main switch when said subsidiary switch is opened.
17. In combination, a main line switch, a controlling device having a plurality of switch members interlocked to operate in a definite sequence, and a mechanical interlock between said main switch and one of said switch members for necessitating open-

ing of the latter prior to closure of the former.

18. In combination, an electro-responsive main line switch, an electromagnetically-operated controlling device having a plurality of switch-members arranged to be operated in a definite sequence, and a mechanical interlocking device controlled by said con-

trolling device for necessitating opening of a predetermined number of said switch-members prior to the closure of said main switch.
